UNITED STATES PATENT OFFICE

145,501

DESIGN FOR A GAME BOARD

Irving Altman, New York, N. Y.

Application July 16, 1945, Serial No. 120,727

Term of patent 7 years

(CL. D34—5)

To all whom it may concern:

Be it known that I, Irving Altman, a citizen of the United States of America, residing at New York, in the county of the Bronx and State of New York, have invented a new, original, and ornamental Design for a Game Board, of which the following is a specification, reference being made to the accompanying drawing, forming a part thereof.

Fig. 1 is a top view of a playing field for a game board embodying my new design;

Fig. 2 is a sectional view taken through line 2—2 of Fig. 1.

In the drawing the solid black outlines surrounding some of the holes indicate color different from that of the outlines surrounding the remaining holes and likewise the heavy lined numbers indicate color different from that of the light lined numbers.

The trapezium at the base of the board indicates the border of an opening.

I claim:

The ornamental design for a game board, substantially as shown and described.

IRVING ALTMAN.
